DESIGN.

—o—

F. MANKEY.

MOLDING.

No. 16,429.

Patented Dec. 29, 1885.

UNITED STATES PATENT OFFICE.

FREDERICK MANKEY, OF WILLIAMSPORT, PENNSYLVANIA.

DESIGN FOR A MOLDING.

SPECIFICATION forming part of Design No. 16,429, dated December 29, 1885.

Application filed November 13, 1885. Serial No. 182,758. Term of patent 7 years.

To all whom it may concern:

Be it known that I, FREDERICK MANKEY, of Williamsport, Lycoming county, Pennsylvania, have invented and produced a new and original Design for Moldings, of which the following is a specification, reference being had to the accompanying photograph, forming part hereof.

On each edge of the molding appear projections A, having inclined sides, and alternating with rectangular recesses or indentations B. At regular intervals along the center line of the molding are annular recesses, each containing a rounded or convex elevation, C. On the face of the molding, and extending from

each annular recess to the adjacent four indentations B, are grooves or channels D.

I claim—

The design for a molding, substantially as herein shown and described, which consists in the projections A, having inclined sides, and alternating with rectangular recesses B on each edge of the molding, and annular recesses, convex elevations C therein, and grooves D on the face of said molding.

FREDERICK MANKEY.
